UNITED STATES PATENT OFFICE.

HENRY BARDSLEY, OF PROVIDENCE, RHODE ISLAND, ASSIGNOR TO CROMPTON & KNOWLES LOOM WORKS, A CORPORATION OF MASSACHUSETTS.

LET-OFF MECHANISM FOR LOOMS.

1,112,668.

Specification of Letters Patent.

Patented Oct. 6, 1914.

Application filed June 5, 1911. Serial No. 631,366.

To all whom it may concern:

Be it known that I, HENRY BARDSLEY, a citizen of the United States, residing at Providence, in the county of Providence and 5 State of Rhode Island, have invented certain new and useful Improvements in Let-Off Mechanism for Looms, of which the following is a specification.

My invention relates to let off mechanism 10 for looms, and particularly to a warp tension regulator in which a torsion spring or weight is used, to produce the tension on the warp beam and warp.

The object of my invention is to improve 15 upon the construction of the ordinary friction let off mechanism, which is adapted to automatically regulate the tension on the warp, as required.

My invention consists in certain novel features of construction of my improvements as 20 will be hereinafter fully described.

In my improvements, I preferably employ 25 a rope or chain, which passes around a friction disk on the warp beam, and a helically coiled torsion spring, or a weight communicates tension to the rope or chain, and on 30 the up and down movement of the whip roll, the tension on the rope or chain will be automatically increased, or decreased, to regulate the tension on the warp, as required.

I have only shown in the drawings a detached portion of a loom, and a let off mechanism, with my improvements in warp tension regulator combined therewith, sufficient 35 to enable those skilled in the art to understand the construction and operation thereof.

Referring to the drawings:—Figure 1 is 40 an end view of a detached portion of a loom frame, and the warp beam, and my improvements in warp tension regulator combined therewith, looking in the direction of arrow *a*, Fig. 3. Fig. 2 shows some of the parts shown in Fig. 1, detached, and in a different position. Fig. 3 is a rear view of 45 the parts shown in Fig. 1, looking in the direction of arrow *b*, same figure. Fig. 4 is a section, on line 4, 4, Fig. 3, looking in the direction of arrow *c*, same figure, showing an inner end view of the parts shown in the 50 lower part of said Fig. 3. Fig. 5 is a rear view of a modified construction of my warp tension regulator, and Fig. 6 is a section, on line 6, 6, Fig. 5, looking in the direction of arrow *b*, same figure.

In the accompanying drawings, 1 is the 55 loom side or end frame, 2 is a cross girt secured to the loom side. The loom side or end frame 1 has suitable bearings 1' for the journals 3' of the warp beam 3; only the beam head at one end of the warp beam is 60 shown in the drawings. The beam head 3 has the brake member or friction disk 4 rigidly connected therewith, of any usual construction, and rotatable with the warp beam 3. A suitable friction or brake member 5, 65 which in the present instance is a rope or cord, is wound around the friction disk 4, and co-operates therewith, and the pressure or drag exerted on the rope 5, determines the tension to which the warp is subjected by the let off mechanism. I have 70 shown the friction member as a rope or cord, but it will be understood that a chain, strap, or band, or any other suitable means, may be used, instead of a rope, to obtain the desired 75 friction. The warp 6 passes over the movable whip roll 7, toward the front of the loom. The whip roll 7 has its journal 7' loosely mounted in an open end slot 8' in a lever 8, see Fig. 1, which has its hub 8'' secured upon a cross shaft 9. The shaft 9 has its ends journaled in a bearing 10' on a stand 10 secured to the loom side, see Fig. 3. Instead of the roll 7 a stationary bar or rod 80 may be used. All of the above mentioned 85 parts may be of any usual and well known construction.

I will now describe my improvements in warp tension regulator. Secured to the loom side 1 and cross girt 2, is a stand 11, see 90 Figs. 1 and 4, which carries a horizontally extending stud 12. A drum 13, Fig. 4, is loosely mounted on the stud 12, which is preferably provided on one end with a ratchet 14, by which the drum 13 may be 95 revolved, to loosen the friction rope 5, by operating the hand lever 15, having a pawl 16 pivotally mounted thereon. A pawl 17 on the stand 11 is adapted to engage and hold the ratchet 14 in the desired position. 100 The drum 13 has a disk 13' thereon, see Fig. 4, to which is secured one end of a helically coiled torsion spring 18. The spring 18 encircles the hub of the drum 13, and has its other end connected to a worm gear 19, 105 which has its hub 19' loosely mounted on the stud 12. The revolution of the worm gear 19, in one, or the other direction, causes

the spring 18 to be tightened or loosened, to give more or less tension to the rope 5 wound on the drum 13.

The worm gear 19 meshes with, and is operated at intervals, by a worm 20, see Fig. 3, which is in this instance fast on a horizontally extending shaft 21, which is loosely mounted in bearings 11' on the stand 11. The outer end of the shaft 21 has secured thereon the ratchet wheels 22, and 23, which have their teeth in this instance extending in opposite directions, as shown in Figs. 1 and 2.

An upright lever 24 has its hub 24' loosely mounted on the shaft 21, and has the downwardly extending arm 24'', which is pivotally connected to a rod head 25, from which a connector or rod 26 leads to an arm, not shown, on a rock shaft, not shown, from which a rocking motion is communicated to the upright lever 24. The upper arm of the upright lever 24 carries a stud 27, on which are loosely pivoted the hubs of two pawls 28, and 29, which in this instance are adapted to engage the ratchet wheels 22, and 23, respectively. A helically coiled torsion spring 30 acts to move downwardly either one of the pawls 28 and 29.

The pawls 28 and 29 are each provided with a stud or projection 28' and 29', which in their inward position, as shown in Fig. 1, rest upon a shield 31'. The shield 31' forms the end of an upwardly extending arm 31, which has its hub 31'' loosely mounted on the shaft 21, and located between the ratchet wheels 22, and 23, see Fig. 3. An ear 31''', which extends from the hub 31'' of the arm 31, has pivotally connected thereto the lower end of an upwardly extending connector, or rod 32. The upper end of said rod 32 is adjustably connected to the swivel head 33, which, through a bolt 34, is pivotally mounted on the end of an arm 35. The arm 35 extends outwardly from the friction disk 36, see Fig. 3, which in this instance, is centrally located, and pivotally mounted on a bolt 37, which loosely extends through the disk 36, and a circular portion 38' on a stand 38, which is secured to a bracket 39 mounted on the loom side 1.

A helically coiled expansion spring 40 encircles the bolt 37, and acts to yieldingly press the friction disk 36 against the circular portion 38', which in this instance is preferably provided with a disk 41, of leather or other suitable material, to increase the friction. A weight 36' on the friction disk 36 acts to counterbalance the arm 35 and connections.

Two set screws 42 are turned into threaded holes in lugs 36'' on the disk 36, and are adapted to engage the engaging end 43' on a downwardly extending arm 43, which has its hub 43'' secured on the end of the whip

roll shaft 9. Another arm 44 extends horizontally from the hub 43'', and has adjustably connected thereto the downward extending rod 45, which is suitably guided in a stand 46 on the loom side 1.

A helically coiled expansion spring 47 encircles the rod 45, and bears at its upper end against the stand 46, and at its lower end against the hub of a hand wheel 48, which is secured on the end of the rod 45. The spring 47 acts, through arm 44 on the shaft 9, to move upwardly the arm 8, and the whip roll 7, against the strain of the warp 6.

The change of the tension on the warp 6 will move up or down the whip roll 7 and the lever 8, and through the rocking motion of the arm 43 on the shaft 9, the end 43' of said arm 43, will engage one or the other of the set screws 42, to turn the friction disk 36, and to move up or down the arm 35 on said disk 36, and move the pawl shield 31' through the connector 32. Said disk 36 prevents the unsteady movement of the pawl shield 31'.

As shown in Fig. 2, the whip roll 7 has a tendency to move upwardly by the diminished tension on the warp. The arm 43 engages, in this instance, the set screw 42, at the right, Fig. 1, and causes the arm 35 on the friction disk 36 to move upwardly. Through intermediate connections to the arm 31, the shield 31' will move to the left in Fig. 2, to allow the pawl 28 on the arm 24 to drop and engage the teeth on the ratchet wheel 22, to turn said ratchet wheel 22 and the worm 20, and the shaft 21, and cause, through the worm gear 19, the spring 18 on the drum 13 to be tightened. The lowering of the whip roll 7 causes the shield 31' to be moved in the opposite direction, and allows the pawl 29 to drop, to engage the ratchet wheel 23, which, through the revolving of the worm 20, will turn the worm gear 19 in the opposite direction, to loosen the tension of the spring 18, as will be readily understood by those skilled in the art.

In Figs. 5 and 6 are shown a modified construction of my warp tension regulator, in which a weight is used instead of a spring.

I will now describe said modified construction. Instead of having the drum 13 rigidly connected with a worm gear 19, a sprocket wheel 49 is fast on the hub 19' of the worm gear 19. A sprocket chain 50 passes around the sprocket wheel 49, and across the loom, then around a second sprocket wheel 51, see Fig. 5, which is loosely mounted on a stud 52 on the stand 11' on the opposite loom side. The upper portion of the sprocket chain 50 has connected thereto, at the left in Fig. 5, by a lug or extension 53', a weight carrier 53, and at the right the lower portion of the sprocket chain 50 is connected, by a projection or lug 54', with the weight carrier 54. The weight carriers 53 and 54 have weights 130

55 thereon. The weight carrier 53 has a roll 56 mounted on a stud 57, and adapted to travel along the upper edge of a weight lever 58, as the sprocket wheel 49 is revolved. 5 The weight lever 58 has its hub 58' pivotally mounted on a stud 59. A link 60 has its lower end pivotally connected to the weight lever 58, and its upper end to an intermediate lever 61, which has its hub 61' pivotally mounted on a stud 62. The intermediate lever 61 has suitably connected therewith the rope or cord 5, which is wound around the friction disk 4. The other weight carrier 54 is provided with a roll 63, loosely 10 mounted on a stud 64, and is adapted to travel along the upper edge of a weight lever 65, which has its hub 65' pivotally mounted on a stud 66. A link 67 has its lower end pivotally connected to the weight lever 65, and its upper end connected to an intermediate lever 68, which has its hub pivotally mounted on a stud 69. The intermediate lever 68 has suitably connected thereto the rope or cord 5', which is wound 15 around the friction disk on the opposite end of the warp beam, not shown.

As is above described, and shown in Fig. 2, the whip roll 7 moves upwardly by the diminished tension of the warp, through the 20 operating parts above described; the shaft 21, and the worm 20 will be turned and cause, through the sprocket wheel 49 and the chain 50 thereon, either one of the weight carriers 53 or 54, on the weight 25 levers 58 and 56, to move inwardly, to cause the tension on the ropes 5 and 5' to be increased.

The lowering of the whip roll 7 causes, through the operation of the ratchet wheel 28, and through the revolution of the worm 20, the worm gear 19 and the sprocket wheel 49 to be turned in the opposite direction, and the weight carrier 57 and the weight 45 carrier 58 to be moved outwardly, as will be readily understood by those skilled in the art.

It will be understood that the details of construction of my improvements may be varied if desired.

Having thus described my invention, what I claim as new and desire to secure by Letters Patent is:—

1. In a let off mechanism for looms, a beam having a friction surface, a whip roll or bar over which the warp passes from said beam, a rope acting on said friction surface to retard the rotation of said beam, a tension device for said rope, and mechanism, controlled by the movement of said whip roll, to automatically regulate the action of said tension device, said mechanism comprising two ratchets, a pawl for each ratchet and means to operate said pawl, a pawl shield, and connections intermediate said pawl shield and said whip roll, said connections including a friction disk device to transmit the movement of said whip roll to said pawl shield, and normally hold said shield in a fixed position.

2. In a let off mechanism for looms, a beam having a friction surface, a whip roll or bar over which the warp passes from said beam, a rope acting on said friction surface to retard the rotation of said beam, a drum 70 loosely mounted on a stud to which drum 75 said rope is attached, a ratchet on said drum, a hand lever carrying a pawl for rotating said ratchet, and a holdfast pawl for said ratchet, a torsion spring on said drum, attached at one end to move with said 80 drum, and attached at its other end to a worm gear, and said worm gear loosely mounted on said stud, a worm in mesh with said worm gear, fast on a horizontal shaft, and said horizontal shaft, loosely mounted 85 in bearings, and two ratchet wheels fast on said shaft, having teeth extending in opposite directions, and a lever loosely mounted on said shaft, a connector from said lever to communicate a rocking motion to said 90 lever, two pawls mounted on the upper end of said lever to engage said ratchet wheels, respectively, a shield to engage said pawls, connections intermediate said shield and a friction disk, and said disk, and connections 95 intermediate said disk and the roll over which the warp passes, the up and down movement of said roll causing the movement of said pawl shield.

HENRY BARDSLEY.
